UNITED STATES PATENT OFFICE.

WALTER W. WINSLOW, OF LAREDO, TEXAS.

LOCK.

No. 885,558.

Specification of Letters Patent. Patented April 21, 1903.

Original application filed April 22, 1907, Serial No. 369,644. Divided and this application filed July 6, 1907.
Serial No. 382,474.

To all whom it may concern:

Be it known that I, WALTER W. WINSLOW, a citizen of the United States, residing at Laredo, in the county of Webb and State of Texas, have invented a new and useful Lock, of which the following is a specification.

This invention has reference to improvements in locks, and its object is to provide a lock which when one of the knobs is turned will give an alarm, whether on the turning of the knob the lock-bolt be thrown or remain inactive.

The present invention relates more particularly to the alarm mechanism, while the means whereby the lock-bolt may be thrown or not, as desired, is shown and described in my application No. 369,644, filed April 22, 1907, for locks, of which application this case is a division.

20 The present invention comprises an alarm mechanism arranged in constant communication with one of the door knobs, which will be the knob situated exterior to the compartment the door of which is controlled by the lock.

25 Since the alarm mechanism is designed to have the function of an ordinary door-bell as well as to give notice of surreptitious attempts to enter the compartment controlled by the lock, there is also provided means whereby the knob controlling the alarm may be disconnected from or connected to the lock-bolt-operating structures at the will of the occupant of the compartment.

30 The invention will be fully understood from the following detailed description, taken in connection with the accompanying drawings forming part of this specification, in which,—

35 Figure 1 is a cross section through the lock and a portion of a door to which it is applied, parts being shown in elevation; Fig. 2 is a face view of the lock; Fig. 3 is a detail view showing the manner of connecting the outer 40 knob to the ringing mechanism; and Fig. 4 is a cross section of the means for coupling the outside knob to the lock-bolt-operating mechanism.

45 Referring to the drawings, there is shown the casing 1 of a lock adapted to be attached to the face of a door. On the exposed face of this lock is secured a bell 2 which may be of any ordinary or approved type and may be provided with any desired style of ringing mechanism capable of being set in operation

by rotary movement imparted thereto. There being many types of such bells on the market, adapted for use in the structures embraced by this invention, it is not deemed necessary to show the internal construction 60 of such a bell.

Extending through the casing from the bell structure is a shaft 3 carrying on the inner face of the casing a pinion 4 seated in a countersunk portion 5 of the door 6, and meshing 65 with this pinion is a gear wheel 7 also seated in a countersunk portion 8 of the door 6.

The gear wheel 7 is mounted upon the spindle 9 of a knob 10. This spindle carries a collar 11 seated in a recess 12 concentric 70 with the countersunk portion 8 in the door, while the shank 13 of the knob 10 bears against a face-plate 14 on the outside of the door. The collar 11 is adjustably secured to the knob spindle by a set-screw 15, so that 75 the structure may be adapted to doors of different thickness, and the knob 10 of this spindle 9 will be confined by the engagement of the collar 11 with the bottom of the recess 12 and the engagement of the shank 13 with the 80 face plate 14.

The spindle 9, after passing through the gear wheel 7, is rounded, as indicated at 16, and near its end is provided with a through slot 17. The rounded portion 16 of this 85 spindle enters the shank 18 of a knob 19. The shank 18 carries a roll-back 20 by means of which the bolt is thrown on the turning of the knob 19, but since the latch structure is in itself not included in the present case but is 90 fully described and claimed in the aforesaid application of which this is a division, no further description of such latch structure is here given.

The knob shank 18 carries a pin 21 having 95 an exterior handle and extending to the interior of the shank where it enters the slot 17 in the end of the knob spindle 9. This pin is held in place by means of a clip spring 22 embracing the shank 18 and yielding sufficiently 100 to permit the pin to be withdrawn from the slot 17 and even from engagement with the shank 18, so that it may be then turned upon the latter out of coincidence with the perforation in the shank 18 through which it 105 passes to reach the slot 17.

Now, let it be supposed that the pin 21 has been withdrawn from the slot 17. Under these circumstances the knob 10 may be freely turned and will not affect the lock since 110

there is then no connection between the latch-operating mechanism and the knob 10, which is located exterior to the compartment controlled by the door 6. But the bell 5 2 being connected through the shaft 3 and pinion 4 with the gear 7, and, therefore, constantly under the control of the knob 10, will be operated and the bell will give an alarm every time the knob 10 is turned. This will 10 apprise the occupant of the room of the fact that some person is turning the knob 10; then, by the occupant manipulating the knob 19, the door may be opened. The bell thus 15 performs the ordinary functions of a door-bell and may likewise serve as an alarm.

When the pin 21 is so located as to engage in the slot 17 the outer knob 10 is then coupled up to the latch mechanism, so that the latch is under the control of said outer 20 knob. But even under these conditions the bell is still active and anyone desiring to enter the compartment will, upon manipulating the knob 10, cause the bell to ring, thus giving notice to the occupant of the 25 room that the knob is being turned and the latch is being thrown to release the door.

Since there is nothing in the appearance of the exterior knob to indicate that there is an alarm mechanism connected therewith, a 30 person attempting to surreptitiously gain access to the compartment through the door would not be led by the appearance of the structure to take any precaution, and would

therefore unwittingly give an alarm and thus warn the occupant of the room that such attempt was being made. Therefore, the bell attachment to the lock operates both as a door-bell and a burglar alarm.

I claim:—

1. In a lock, a bell, a knob in constant connection with the bell to ring the same whenever the knob is manipulated, another knob in constant connection with the latch bolt of the lock to operate the same whenever the last-named knob is manipulated, and means 45 for connecting the first-named knob to the second-named knob to operate the latch bolt and bell simultaneously when either knob is manipulated.

2. A lock comprising a suitable lock casing, 50 a bell carried thereby, a knob in constant operative relation to the latch-bolt of the lock, another knob, a knob spindle fast to the last-named knob and extending into the shank of the first-named knob, means for 55 coupling and uncoupling said knobs through the spindle carried by the second-named knob, a gear wheel on said spindle, and gear connections from said gear wheel to the bell.

In testimony that I claim the foregoing as 60 my own, I have hereto affixed my signature in the presence of two witnesses.

WALTER W. WINSLOW.
